UNITED STATES PATENT OFFICE

JOHN A. ANDERSON, OF BRIDGEPORT, CONNECTICUT, ASSIGNOR TO THE BRIDGEPORT HARDWARE MANUFACTURING CORPORATION, OF BRIDGEPORT, CONNECTICUT, A CORPORATION OF CONNECTICUT

VALVE-SPRING LIFTER

Application filed May 14, 1928. Serial No. 277,449.

This invention relates to valve spring lifting tools such as are used for lifting or compressing the valve springs of automobile engines to facilitate removal of the valve, and has for an object to provide a tool of this character which will be very rigid when in use and will hold the spring compressed without danger of yielding or giving away and permitting the spring to expand during the 10 operation on the valve with the consequent danger of injury to the operator.

It is also an object of the invention to provide a tool of this character which may be more easily inserted between the spring and 15 its abutment than tools now generally in use.

With the above and other objects in view, the invention consists in certain novel features of construction, combinations and arrangements of parts which will be more fully 20 described, a construction embodying this invention being shown in the accompanying drawing. In this drawing,

Fig. 1 is a top plan view of a valve spring lifting tool embodying my invention.

Fig. 2 is a side elevation thereof with a portion of one of the jaw elements broken away to more clearly show the construction.

Fig. 3 is a detail section substantially on line 3—3 of Fig. 1 showing the jaws in closed 30 position.

Fig. 4 is a front end elevation of the device looking from the left of Fig. 2.

Fig. 5 is a top plan view of the jaw end of the device showing a slightly different construction of jaws.

Fig. 6 is a side elevation of the form shown in Fig. 5.

Fig. 7 is a detail plan view of the forward end of one of the handle levers showing the stop element carried thereby.

Fig. 8 is a side elevation thereof looking from the bottom of Fig. 7 and showing the pivot pin in section, and

Fig. 9 is a view similar to Fig. 8 showing a slightly different construction.

This tool, as illustrated comprises a pair of handle levers 10 and 11 which are pivoted together at 12, and it will be noted that these levers are curved so that they do not cross 50 at this pivot but extend away from each

other on opposite sides of the pivot. To the free ends of these levers opposite to the handles are pivoted forked jaws 13 and 14, the jaw 13 being pivoted to the lever 10 at 15, while the jaw 14 is pivoted to the lever 11 at 16. In order to strengthen the device it is preferred that the jaws be recessed at these pivots, as indicated at 17, to receive the ends of their respective levers, so that there will be bearings for the pivot pins in the jaw structure on both sides of the levers. Each jaw has a rearward extension 18 which projects beyond the pivot 12 to the opposite side thereof and are pivoted at 19 to each other between the handles. It will be apparent from this arrangement that as the handles of the levers 10 and 11 are forced together or toward each other their opposite ends carrying the pivots 15 and 16 will separate or move away from each other, carrying with them the jaws 13 and 14 and swinging them about the pivot 19. Thus as the handles are forced together the jaws are separated, and if they are first inserted between the lower end of a valve spring and its abutment they will lift one end of this spring and compress it.

Hitherto in this type of devices means have been provided for holding the jaws separated to prevent their collapsing under pressure of the spring. These have commonly been mounted on the pivot 12 or between the handle portions of the lever. These arrangements are objectionable because the holding means were so far removed from the jaws and the leverage was so great the jaws themselves, their supports or pivots would yield or spring permitting the jaws to collapse and bending the device out of shape.

In the present construction I have provided an improved catch means which is located directly between the two jaws or practically in the line of the force applied, so that the forces are imparted directly to this catch, giving a much more rigid and reliable construction. This arrangement comprises a catch lever 20 mounted on the pivot 16 for one of the jaws, preferably the lower jaw. This lever extends directly across from the jaw 14 to the jaw 13 and has on its forward edge a plurality of stop shoulders 21, which

may be provided by a series of notches in the edge of the lever. The jaw 13 carries adjacent its pivot 15 a stop element 22 adapted to cooperate with these stop shoulders or notches 5 to hold the jaws separated under pressure of the spring being lifted. The lever 20 curves backwardly from the transverse portion thereof to provide an operating extension 23 extending toward the operating handles, and 10 may have a finger or thumb lug 24 adjacent one of the handles where it is easily accessible for releasing this catch lever. A coil spring 25 is mounted on the pivot pin 16 and has its opposite free ends 26 and 27 engaging under 15 the jaw 14 and the rear edge of the lever 20 respectively, to thus tend to swing the lever 20 counterclockwise or to the left, as viewed in Fig. 2, about its pivot 16 and retain its forward edge against the stop element 22, so 20 that as the jaws are operated to separate them the stop 22 will automatically engage one of the stop shoulders 21 to hold the jaws in the separated position as soon as the pressure on the handles is released. If it is desired to 25 release the valve spring or permit the jaws to collapse or move together, all that is necessary is to force the handles together sufficiently to release the pressure on the catch lever and then press down on the lug 24 which 30 will swing this lever away from the stop element 22 and permit the jaws to move toward each other.

As shown in Figs. 1 and 2, the stop element 22 is a pin mounted in the handle lever 35 as shown more clearly and on a larger scale in Figs. 7 and 8. It may, however, be formed as a stop lug 22' integral with the lever if desired, as shown in Fig. 9.

As shown in Figs. 1, 2 and 3, the lower 40 forked jaw 14 is extended at its free edge 28 beyond the free end 27 of the upper jaw, and the jaw 14 is provided with a shoulder 30 spaced rearwardly from the free end 28 at substantially the distance of the free end 29 45 of the upper jaw as shown. The shoulder is of a height approximately equal to the thickness of the free end of the other jaw 13, so that when the jaws are together, as shown in Fig. 3, the upper surfaces thereof will be in 50 substantially the same plane. It will thus be seen from an inspection of Fig. 3 that when in this position the jaws are in effect of a single thickness at their free end and have practically continuous surface leading from this 55 free end on both the upper and lower sides thereof. It will be obvious that this greatly facilitates the insertion of the jaws between the end of the spring and its abutment in using the device.

60 In Figs. 5 and 6 is shown a somewhat different construction of jaw especially adapted for use on certain types of valve springs in which it is not feasible to insert the jaw between the end of the spring and its abutment. 65 The lower jaw 31 is straight while the upper

jaw 32 has the portion 33 on one side of its notch 34 bent downwardly while the portion 35 on the other side of this notch is bent upwardly out of the plane of the jaw, so that these portions may be inserted between two 70 adjacent convolutions of the spring, and when so inserted will follow approximately the curve of the convolutions and will seat firmly in the spring without danger of being forced out by camming action of the inclined 75 portions of the spring.

It will be apparent from the foregoing description that the catch to hold the jaws separated against the pressure of the spring is located as near as possible in the direct line 80 of its pressure and practically directly between the two jaws, so that the pressure is transmitted immediately and directly to the holding means, and there is very little tendency to twist the jaws out of position and 85 there is nothing to spring or yield to cause the catch to give away and permit the jaws to collapse. It will also be apparent that the improved jaw construction illustrated will greatly facilitate insertion of the jaws between the spring and its abutment. 90

Having thus set forth the nature of my invention, what I claim is:

1. In a valve spring lifter, a pair of handle levers pivoted together intermediate the ends 95 thereof, a pair of jaws pivoted to the respective free ends thereof on the opposite side of the pivot from the handles, a catch lever pivoted to one of said jaw pivots and provided with stop shoulders, and cooperating stop means located adjacent the pivot for the other jaw. 100

2. In a valve spring lifter, a pair of handle levers pivoted together, a pair of jaws pivoted one to each lever and arranged to separate as the handles are moved toward each other, a catch lever pivoted to one of the jaws adjacent the pivotal connection of said jaw to its lever and extending laterally therefrom to the other jaw, and cooperating means on the catch lever and closely adjacent the latter jaw to hold the jaws separated against pressure tending to force them together. 110

3. In a valve spring lifter, a pair of handle levers pivoted together, a pair of jaws pivoted one to each lever and arranged to separate as the handles are moved toward each other, a catch lever pivoted to one of said jaw pivots and extending laterally therefrom toward the other jaw, said catch lever being provided with a series of stop shoulders, and a stop lug mounted adjacent the pivot for the second lever and adapted to cooperate with said shoulders to hold the jaws separated against pressure tending to move them together. 120

4. In a valve spring lifter, a pair of handle levers pivoted together intermediate the ends thereof, a pair of jaws pivoted to the respective free ends thereof on the opposite side of 125

the pivot from the handles, a catch lever pivoted to one of said jaw pivots and extending laterally therefrom toward the other jaw, said lever being provided with a series of stop shoulders and an operating extension extending toward the handles, and a stop lug adjacent the pivot for the second jaw adapted to cooperate with said stop shoulders to hold the jaws separated.

10 5. In a valve spring lifter, a pair of handle levers pivoted together intermediate their ends, a pair of opposed jaws pivoted one to each lever on the opposite side of the pivot from the handles and provided with extensions pivoted together on the opposite side of the pivot between the handles, a catch lever pivoted on the pivot between one of said jaws and its lever and extending laterally therefrom toward the other jaw, said lever having
15 a series of stop shoulders, a stop lug adjacent the pivot for the second jaw adapted to cooperate with said shoulders to hold the jaws separated, said lever being provided with an operating extension projecting toward said
20 handles, and a spring tending to turn the catch lever on its pivot and hold it against said lug.

6. In a valve spring lifter, a pair of handle levers pivoted together, a pair of jaws
30 connected to the levers and arranged to be separated as the handles are moved toward each other, a stop lever extending between the jaws and pivoted directly to one of them, stop means on the lever and stop means closely adjacent the other jaw cooperating with the first stop means to hold the jaws separated, a spring tending to operate the catch lever to hold said stop means in engagement, and means for operating the catch lever against
35 the action of the spring.

7. In a valve spring lifter, a pair of handle levers pivoted together, a pair of forked jaws connected to the levers and arranged to be separated as the handles are moved toward each other, one of said jaws extending beyond
45 the other jaw at its free end and provided with a recess spaced from its free end into which the end of the shorter jaw may seat when the jaws are closed together.

50 8. In a valve spring lifter, a pair of handle levers pivoted together, a pair of forked jaws connected to the levers and arranged to be separated as the handles are moved toward each other, one of said jaws being extended
55 beyond the other jaw and provided with a shoulder spaced backwardly from its free edge at substantially the distance of the free end of the second jaw from said edge, said shoulder being approximately the height of
60 the thickness of the second jaw so that the two jaws form a substantially continuous surface when closed.

In testimony whereof I affix my signature.
